ATTORNEY

UNITED STATES PATENT OFFICE.

JOHN C. DARNALL, OF CINCINNATI, OHIO.

RACK OR TRAY FOR DRINKING-GLASSES AND LIKE PURPOSES.

1,263,866.

Specification of Letters Patent. Patented Apr. 23, 1918.

Application filed June 26, 1916. Serial No. 106,010.

To all whom it may concern:

Be it known that I, JOHN C. DARNALL, a citizen of the United States of America, and a resident of Cincinnati, in the county 5 of Hamilton and State of Ohio, have invented a certain new and useful Improvement in Racks or Trays for Drinking-Glasses and like Purposes, of which the following is a specification.

10 This invention relates to improvements in racks or trays used in supporting drinking-glasses and the like, especially in connection with the draining thereof after cleansing and rinsing and, also, still more especially 15 in connection with the sterilization or purification of the inner and outer surfaces of the said glasses and other objects used for drinking or food serving purposes.

The principal object of the invention 20 herein is to produce a grated or cross-barred rack or tray in which the bars are each shaped and bent upwardly and are then duly connected together at right-angles so as to form a series of conical, upright, glass-supporting crossed-members or individual, crossed-pedestals that enter or telescope within the inverted glasses to support them entirely independent of each other and so 25 that the minimum of contact only of the clean inner-surfaces of the glasses and the several adjacent edges of the parts of the pedestals shall be presented to each other in the use of the trays and whereby the chance 30 of lodgment of any germs or of any germ-carrying fluids or substances is reduced to a minimum, and whereby, also, the proper 35 drying of the glasses without any distinctive or perceptible marks thereon to mar the surfaces thereof is effected, and, finally, in presenting glasses or tumblers for use that are 40 absolutely clean and in a thoroughly sanitary condition.

The details of structure of my grated rack or tray will be fully hereinafter described 45 and then more particularly pointed out in the claim that follows:

In the accompanying sheet of drawings, Figure 1 is a plan view of the grated rack or tray embodying my invention herein; 50 Fig. 2, (shown longitudinally of the sheet, for the sake of ample space), a longitudinal elevation; and Fig. 3, a transverse section of the tray taken on the line of one of the riveted-intersections of a double tier of trays

having pedestals or protuberant glass-supports, and including the upright walls of a chamber in which the tray herein is to be used. (Glasses are shown, in this view, in place for free circulation of hot air and sterilizing-medium on the conical-supports of 55 the tray.)

The grated rack or tray is composed preferably of narrow metal bars or strips 1 and 2 that cross each other at right-angles and are of any desired number to suit the number of glasses to be held on the tray. In Fig. 1, however, I have shown but two longitudinal bars 1 and four transverse bars 2, they being held together at their several intersections by means of rivets 3, and rivets 65 4 being used at the opposite ends of the bars to secure them to a rectangular, skirting frame-bar 5, the latter being made of the same thin sheet-metal strip-material as that of the crossed bars 1 and 2 when the racks 70 75 are to be used in the upper tiers.

Each of the bars 1 and 2 is bent upwardly at suitable intervals apart into a conical pedestal or crown that is composed of a horizontal or flat apex 6 that has downwardly-sloping sides 7, the latter being diverted or flexed outwardly at 8 so as to make a definite or a little more decided stop for the flared mouth 9 of the inverted glass 10 80 telescopically placed thereon. The pairs of 85 sloping sides 7 of adjacent pedestals are connected by the curved bottom-ligaments 7^a.

The glass 10 is of the ordinary tapered form with a flaring mouth and, in this instance, is that of the type used at soda-fountains in the service of many kinds of beverages where cleanliness is predominant and where glasses must needs be sterilized or otherwise similarly treated from a sanitary stand-point and the lodgment of germs 90 95 prevented.

Each of the glasses is placed in an inverted position so that its mouth shall encompass or telescope the four upright bars forming an open skeleton frame or supporting pedestal and with but the open mouth of the glass resting with the least possible contact on said four metal bars of the pedestal, as best shown in Fig. 3. It is obvious that the glasses need not necessarily be flared, as shown in Fig. 3, but they may be of the ordinary tapered type and not flared at all along the drinking-edge 100 105

thereof and still such drinking-edge contact at the least degree with the outer faces of the said four metal bars of the pedestal. Such minute contact of the drinking-edge 5 of the glass with the flat bars of the pedestal and with no other part of the glass in contact with any other object whatever enables the perfect circulation of hot air or gases, or sterilizing-medium within the glass 10 as well as on its outer face so as to derive a perfectly clean and sanitary drinking-glass.

In Fig. 3 I show the bottom tray as having an open rectangular frame of angle- 15 iron sides 11, instead of the light frame-bars 5 of the upper tiers of trays. The sides 11 are duly connected at their opposite ends by means of the same material and furnish a stiff and strong framing-support for the 20 tray that means a perfect circulation or rising of the drying and sterilizing medium within the chamber or oven (whose side-walls 12 and 13 only are shown in said Fig. 3). On the inner faces of said side-walls 25 12 and 13 I provide L-shape or angle irons 14 that are duly riveted in place and intended as guide-ways and supports for the angle-iron inclosing-frame of the bottom-tray. The bottom-tray and a number of 30 35 tiers of trays carried thereby can be readily handled to and from the supports 14 in the sterilizing process, and said bottom-tray is also adapted to be readily handled to and from the oven for putting it and its tiers of trays in position for convenient use.

The trays may be used in tiers, each supported by the glasses that are on the tray beneath, as shown in Fig. 3, wherein each 40 horizontal apex 6 of the flat, longitudinal bar 1 of the upper tier of pedestals rests upon the dished-bottom 15 of the glass beneath and so that contact is reduced to a minimum at that point. The upper tiers of 45 glasses are not mounted on trays having heavy angle-iron frames, as but one lower supporting-frame is sufficient, and any desired number of tiers of trays may be supported thereby when it is necessary to place 50 a greater or lesser number of them within

the sterilizing-oven and remove them therefrom.

The glasses or tumblers being circular and the metal bars 1 and 2 being flat, the points of supporting-contact are so slight that no 55 germs can lodge between them, and the sterilization of said glasses or tumblers is perfected through the said grated pedestals or crowns into and around the said glasses or tumblers, with a free circulation of the hot 60 air or steam at all times.

In Fig. 3 I have shown a straight-sided drinking-glass 10^a, mounted in inverted position on the upper pedestal, to the left, such pedestal being the only one in this 65 view to have a definite or decided stop 8 for the lip or drinking-edge of the glass. It is in connection with said straight-sided glass that I use said definite or decided stop 8, because, if the sloping sides 7 were not 70 flexed, the said straight-sided glass would have a tendency to be forced upwardly by the resiliency of said sloping sides 7 of the pedestal and be only very slightly supported at the upper edge of each of the sloping 75 sides 7 of the pedestal and liable to topple over. Ordinarily it would not be necessary to flex or bend the sloping sides 7 of the pedestals for the flared glasses shown in 80 said view.

The rack is especially useful when removed with its contents from the sterilizer and placed on the customary drain-board or the like in position for handling the said contents and so that the latter never touch 85 any other support to become foul or infected.

I claim:—

A rack for drinking-glasses or the like comprising rows of pedestals or grated supports of truncated-cone form, each cone being composed of flat-metal strips that cross and are secured to each other at right-angles and with intervening V-shape ligaments and are adapted to telescopically-support the 95 said drinking-glasses or the like, each in inverted position within a sterilizing-oven or on serving-counters.

JOHN C. DARNALL.
